UNITED STATES PATENT OFFICE.

THOMAS E. HIGGINS, OF PHILADELPHIA, PENNSYLVANIA.

DESIGN FOR A POISON-ALARM DEVICE.

48,894.

Specification for Design.

Patented Apr. 18, 1916.

Application filed May 20, 1915. Serial No. 29,428. Term of patent 14 years.

To all whom it may concern:

Be it known that I, THOMAS E. HIGGINS, a citizen of the United States, residing in Philadelphia, in the county of Philadelphia, State of Pennsylvania, have invented a new, original, and ornamental Design for a Poison-Alarm Device, illustrated in the accompanying drawing, in which—

Figure 1 is a view in elevation of one side of the said device showing my new design; Fig. 2 is a view in elevation of the side of

the same opposite to that shown in Fig. 1; and Fig. 3 is a side view of the same taken at right angles to the views shown in Figs. 1 and 2.

I claim:—

The ornamental design for a poison alarm device, as shown.

THOMAS E. HIGGINS.

In the presence of—

HAROLD J. BOWMAN,

JOHN H. STEBBINS.

Copies of this patent may be obtained for five cents each, by addressing the "Commissioner of Patents, Washington, D. C."
